UNITED STATES PATENT OFFICE.

ARTHUR BATES, OF LEICESTER, ENGLAND, ASSIGNOR TO UNITED SHOE MACHINERY CORPORATION, OF PATERSON, NEW JERSEY, A CORPORATION OF NEW JERSEY.

LASTING MACHINE.

Application filed May 16, 1921. Serial No. 470,161.

To all whom it may concern:

Be it known that I, ARTHUR BATES, a subject of the King of England, residing at Leicester, Leicestershire, England, have invented certain improvements in Lasting Machines, of which the following description, in connection with the accompanying drawings, is a specification, like reference characters on the drawings indicating like parts in the several figures.

This invention relates to mechanism applicable to machines, in which a number of steps or operations are performed in each cycle, for varying the portion of time devoted to one step or operation or to certain operations while maintaining the entire time consumed by the cycle constant. The invention is herein shown, by way of example, as applied to a machine of the type disclosed in United States Letters Patent No. 584,744, granted June 15, 1877, on application of Ladd & McFeely. In machines of this type a gripper operates upon successive portions of the upper step by step about the periphery of the shoe to updraw and overlay the upper upon the shoe bottom.

The problem of the designers and users of such machines has been to secure from them thorough stretching of the upper and the conforming of it to the last while dealing adequately with the various working conditions occasioned by various kinds and conditions of upper stock from which the stretch is to be removed in lasting and also to obtain from the machines large or increased capacity of production. The working out of a satisfactory solution of this problem has engaged the attention of many skilled in the art; one advance toward this end, which has achieved commercial success, being disclosed in United States Letters Patent No. 1,060,967, granted May 6, 1913, on my application, wherein by overlapping of the operations more time for the thorough performance thereof was secured without loss of output. The present invention is illustrated herein in its application to the machine disclosed in my said prior patent.

It is an object of the present invention to meet this problem of thoroughly stretching the upper by securing more time in the cycle for the upper stretching operation without substantially, if at all, increasing the total time taken for the cycle of operations. It

is to be understood, however, that the invention in its broader aspects is not limited in its application to this particular type of machine or to dealing with an upper stretching operation.

A feature of the invention consists in an organization including a plurality of means or instrumentalities for performing a succession of operations upon the work in each cycle, common operating means for operating the instrumentalities in timed relation, a driving member arranged for rotation at uniform angular velocity and means between the driving member and the common operating means acting to retard movement of said operating means relatively to the driving member while one of said instrumentalities is operating, and for accelerating movement of said operating means above that of the driving member at another time in the cycle of the machine. As herein shown, the invention is utilized to increase the time devoted to the updrawing of the upper in a hand method machine relatively to the time consumed by the machine in completing the cycle and without increasing the time occupied by the whole cycle. The particular time interval best suited for the particular operation in question can be obtained without the necessity of correspondingly varying the time consumed in other operations of the machine such as would be brought about if the normal speed of the cam shaft of the machine was merely altered to another uniform speed. Moreover, the desired result can thus be obtained without the need of redesigning the existing cams or other timing mechanism of the machine to do which, of course, would involve great inconvenience and expense in view of the machines already in use, and would necessitate the redesigning of machines of this type.

Another feature of the invention consists in the combination with a driving member, a shaft and operating instrumentalities actuated in common by the shaft to perform a succession of operations, of means between the driving member and the shaft operating in each cycle to diminish the movement of the shaft relatively to that of the driving member for a part of its cycle, to increase the angular movement of the shaft relatively to that of the driving member in another part of the cycle,

and to maintain for a portion of the cycle the speed of the driving member and the shaft the same. As herein shown a master cam is provided which is stationary, and 5 connections between the driving member or pulley and the shaft are controlled by the master cam to cause the shaft in one portion of the cycle to move slower than the driving pulley and in another portion faster. 10 Preferably and as shown, during certain portions of the cycle the master cam maintains the movement of the shaft the same as that of the driving pulley, that is, there is no relative movement between the 15 driving member and the driven member or shaft.

By this construction the time lost in one portion of the cycle by reducing the angular velocity of the shaft, for instance, the cam 20 shaft of a hand method machine, to secure more time for the upper stretching operation, may be made up during each revolution of the cam shaft so that the total time for the completion of the machine cycle is 25 unaffected. Moreover, the speeding up of the cam shaft beyond the hitherto normal speed to recover the lost time may be non-uniformly distributed over the remainder of the cycle and, as shown, it is localized to 30 occur in the concluding portion of the cycle, and, in fact, as applied to the hand method machine, may occur in two separate stages respectively between the completion of the updraw and the commencement of the 35 wiping operation and between the conclusion of the tack driving and the end of the cycle.

These and other features of the invention will appear more fully from the following 40 description when read in connection with the accompanying drawings and will be pointed out in the appended claims.

In the drawings,

Fig. 1 is a perspective view of the operating means and instrumentalities of a hand method lasting machine equipped with the 45 present invention,

Fig. 2 is a rear view of mechanism embodying this invention, and

Fig. 3 is a side view of the parts shown in Fig. 2.

Since the construction and operation of the hand method machine in which the present invention is herein shown as embodied by way of illustration is fully described in the above-mentioned patents, a brief description only of the machine will now be given.

In Fig. 1 of the drawing a construction 60 embodying the present invention, together with the operating instrumentalities of the hand method machine and the mechanism for operating them, is shown, the frame of the machine being omitted for the sake 65 of clearness of illustration. A cam shaft

4 carries a series of cams by which all of the operating instrumentalities are actuated, the gripper 6 being closed upon the work by the action of the edge face of a cam block 8 acting through an arm 10 on a rock-shaft 12 which carries an arm 14 arranged to move downwardly the upper or movable jaw 15 of the gripper. The gripper 6 is moved vertically to effect updrawing or stretching action on the upper by an updraw lever 16 pivoted at 18 and operated by a cam 20 on the cam shaft 4. The overdraw movement of the gripper to lay the upper over the shoe bottom is derived from a cam on the rear face of the cam block 8 through a push rod 22 and spring arm 24. The lateral and plaiting movements of the gripper are effected by the movement of an oscillating driver 26 operated through a lever 28 by a cam path 30 in the front face of the block 8, these movements being controlled at the will of the operator by a rod 32 connected to a knee lever (not shown). The combined tack block and wiper 34 is attached to a slide 36 operated by a cam 38 through a lever 40. The driver 42 is operated to drive the tack, delivered to the tack block 34 in any known manner, after the lower face of the tack block has acted to wipe the upper over the shoe bottom and near the completion of the cycle of the machine.

In the operation of the mechanism above described the first 100 degrees or thereabouts of angular movement of the cam shaft 4 from what may be considered as the starting point, for instance when the grippers are opened, is devoted to the seizing of the upper by the gripper which, during this movement of the cam shaft, is moved toward the upper by the cam 20 and closed upon the upstanding margin of the upper by the cam 8. In the next 40 degrees or thereabouts of the movement of the cam shaft the major portion, if not all, of the straining of the upper and the pulling of it inwardly over the edge of the last are performed, the updrawing continuing through the whole of the 40 degrees of said movement, the overdraw being in action for say the last 10 degrees of this 40-degree portion, and the plaiting action of the gripper, if employed, starting at the same point in the angular movement of the cam shaft as the updraw but continuing to say 200 degrees from the starting point of the cycle. During the remainder of the cycle there are two portions or stages of the rotation of the cam shaft in which none of the operating instrumentalities described has any substantial operative movement. One of these stages (a) occurs between the conclusion of the 40-degree movement mentioned and the commencement of the overwiping on the shoe bottom by the wiper 34 and amounts 120 to 130 degrees. The other stage (b) occurs between the completion of the overwiping and the commencement of the updrawing for the next cycle and amounts to 125 degrees. The cam block 8 is provided with a cam 110 which is actuated by a cam 115 on the cam shaft 4 to effect the lateral and plaiting movements of the gripper 6. The cam 115 is actuated by a cam 120 on the cam shaft 4 through a lever 125 and a cam 130 on the cam block 8. The cam 130 is actuated by a cam 135 on the cam shaft 4 through a lever 140 and a cam 145 on the cam block 8. The cam 145 is actuated by a cam 150 on the cam shaft 4 through a lever 155 and a cam 160 on the cam block 8. The cam 160 is actuated by a cam 165 on the cam shaft 4 through a lever 170 and a cam 175 on the cam block 8. The cam 175 is actuated by a cam 180 on the cam shaft 4 through a lever 185 and a cam 190 on the cam block 8. The cam 190 is actuated by a cam 195 on the cam shaft 4 through a lever 200 and a cam 205 on the cam block 8. The cam 205 is actuated by a cam 210 on the cam shaft 4 through a lever 215 and a cam 220 on the cam block 8. The cam 220 is actuated by a cam 225 on the cam shaft 4 through a lever 230 and a cam 235 on the cam block 8. The cam 235 is actuated by a cam 240 on the cam shaft 4 through a lever 245 and a cam 250 on the cam block 8. The cam 250 is actuated by a cam 255 on the cam shaft 4 through a lever 260 and a cam 265 on the cam block 8. The cam 265 is actuated by a cam 270 on the cam shaft 4 through a lever 275 and a cam 280 on the cam block 8. The cam 280 is actuated by a cam 285 on the cam shaft 4 through a lever 290 and a cam 295 on the cam block 8. The cam 295 is actuated by a cam 300 on the cam shaft 4 through a lever 305 and a cam 310 on the cam block 8. The cam 310 is actuated by a cam 315 on the cam shaft 4 through a lever 320 and a cam 325 on the cam block 8. The cam 325 is actuated by a cam 330 on the cam shaft 4 through a lever 335 and a cam 340 on the cam block 8. The cam 340 is actuated by a cam 345 on the cam shaft 4 through a lever 350 and a cam 355 on the cam block 8. The cam 355 is actuated by a cam 360 on the cam shaft 4 through a lever 365 and a cam 370 on the cam block 8. The cam 370 is actuated by a cam 375 on the cam shaft 4 through a lever 380 and a cam 385 on the cam block 8. The cam 385 is actuated by a cam 390 on the cam shaft 4 through a lever 395 and a cam 400 on the cam block 8. The cam 400 is actuated by a cam 405 on the cam shaft 4 through a lever 410 and a cam 415 on the cam block 8. The cam 415 is actuated by a cam 420 on the cam shaft 4 through a lever 425 and a cam 430 on the cam block 8. The cam 430 is actuated by a cam 435 on the cam shaft 4 through a lever 440 and a cam 445 on the cam block 8. The cam 445 is actuated by a cam 450 on the cam shaft 4 through a lever 455 and a cam 460 on the cam block 8. The cam 460 is actuated by a cam 465 on the cam shaft 4 through a lever 470 and a cam 475 on the cam block 8. The cam 475 is actuated by a cam 480 on the cam shaft 4 through a lever 485 and a cam 490 on the cam block 8. The cam 490 is actuated by a cam 495 on the cam shaft 4 through a lever 500 and a cam 505 on the cam block 8. The cam 505 is actuated by a cam 510 on the cam shaft 4 through a lever 515 and a cam 520 on the cam block 8. The cam 520 is actuated by a cam 525 on the cam shaft 4 through a lever 530 and a cam 535 on the cam block 8. The cam 535 is actuated by a cam 540 on the cam shaft 4 through a lever 545 and a cam 550 on the cam block 8. The cam 550 is actuated by a cam 555 on the cam shaft 4 through a lever 560 and a cam 565 on the cam block 8. The cam 565 is actuated by a cam 570 on the cam shaft 4 through a lever 575 and a cam 580 on the cam block 8. The cam 580 is actuated by a cam 585 on the cam shaft 4 through a lever 590 and a cam 595 on the cam block 8. The cam 595 is actuated by a cam 600 on the cam shaft 4 through a lever 605 and a cam 610 on the cam block 8. The cam 610 is actuated by a cam 615 on the cam shaft 4 through a lever 620 and a cam 625 on the cam block 8. The cam 625 is actuated by a cam 630 on the cam shaft 4 through a lever 635 and a cam 640 on the cam block 8. The cam 640 is actuated by a cam 645 on the cam shaft 4 through a lever 650 and a cam 655 on the cam block 8. The cam 655 is actuated by a cam 660 on the cam shaft 4 through a lever 665 and a cam 670 on the cam block 8. The cam 670 is actuated by a cam 675 on the cam shaft 4 through a lever 680 and a cam 685 on the cam block 8. The cam 685 is actuated by a cam 690 on the cam shaft 4 through a lever 695 and a cam 700 on the cam block 8. The cam 700 is actuated by a cam 705 on the cam shaft 4 through a lever 710 and a cam 715 on the cam block 8. The cam 715 is actuated by a cam 720 on the cam shaft 4 through a lever 725 and a cam 730 on the cam block 8. The cam 730 is actuated by a cam 735 on the cam shaft 4 through a lever 740 and a cam 745 on the cam block 8. The cam 745 is actuated by a cam 750 on the cam shaft 4 through a lever 755 and a cam 760 on the cam block 8. The cam 760 is actuated by a cam 765 on the cam shaft 4 through a lever 770 and a cam 775 on the cam block 8. The cam 775 is actuated by a cam 780 on the cam shaft 4 through a lever 785 and a cam 790 on the cam block 8. The cam 790 is actuated by a cam 795 on the cam shaft 4 through a lever 800 and a cam 805 on the cam block 8. The cam 805 is actuated by a cam 810 on the cam shaft 4 through a lever 815 and a cam 820 on the cam block 8. The cam 820 is actuated by a cam 825 on the cam shaft 4 through a lever 830 and a cam 835 on the cam block 8. The cam 835 is actuated by a cam 840 on the cam shaft 4 through a lever 845 and a cam 850 on the cam block 8. The cam 850 is actuated by a cam 855 on the cam shaft 4 through a lever 860 and a cam 865 on the cam block 8. The cam 865 is actuated by a cam 870 on the cam shaft 4 through a lever 875 and a cam 880 on the cam block 8. The cam 880 is actuated by a cam 885 on the cam shaft 4 through a lever 890 and a cam 895 on the cam block 8. The cam 895 is actuated by a cam 900 on the cam shaft 4 through a lever 905 and a cam 910 on the cam block 8. The cam 910 is actuated by a cam 915 on the cam shaft 4 through a lever 920 and a cam 925 on the cam block 8. The cam 925 is actuated by a cam 930 on the cam shaft 4 through a lever 935 and a cam 940 on the cam block 8. The cam 940 is actuated by a cam 945 on the cam shaft 4 through a lever 950 and a cam 955 on the cam block 8. The cam 955 is actuated by a cam 960 on the cam shaft 4 through a lever 965 and a cam 970 on the cam block 8. The cam 970 is actuated by a cam 975 on the cam shaft 4 through a lever 980 and a cam 985 on the cam block 8. The cam 985 is actuated by a cam 990 on the cam shaft 4 through a lever 995 and a cam 1000 on the cam block 8. The cam 1000 is actuated by a cam 1005 on the cam shaft 4 through a lever 1010 and a cam 1015 on the cam block 8. The cam 1015 is actuated by a cam 1020 on the cam shaft 4 through a lever 1025 and a cam 1030 on the cam block 8. The cam 1030 is actuated by a cam 1035 on the cam shaft 4 through a lever 1040 and a cam 1045 on the cam block 8. The cam 1045 is actuated by a cam 1050 on the cam shaft 4 through a lever 1055 and a cam 1060 on the cam block 8. The cam 1060 is actuated by a cam 1065 on the cam shaft 4 through a lever 1070 and a cam 1075 on the cam block 8. The cam 1075 is actuated by a cam 1080 on the cam shaft 4 through a lever 1085 and a cam 1090 on the cam block 8. The cam 1090 is actuated by a cam 1095 on the cam shaft 4 through a lever 1100 and a cam 1105 on the cam block 8. The cam 1105 is actuated by a cam 1110 on the cam shaft 4 through a lever 1115 and a cam 1120 on the cam block 8. The cam 1120 is actuated by a cam 1125 on the cam shaft 4 through a lever 1130 and a cam 1135 on the cam block 8. The cam 1135 is actuated by a cam 1140 on the cam shaft 4 through a lever 1145 and a cam 1150 on the cam block 8. The cam 1150 is actuated by a cam 1155 on the cam shaft 4 through a lever 1160 and a cam 1165 on the cam block 8. The cam 1165 is actuated by a cam 1170 on the cam shaft 4 through a lever 1175 and a cam 1180 on the cam block 8. The cam 1180 is actuated by a cam 1185 on the cam shaft 4 through a lever 1190 and a cam 1195 on the cam block 8. The cam 1195 is actuated by a cam 1200 on the cam shaft 4 through a lever 1205 and a cam 1210 on the cam block 8. The cam 1210 is actuated by a cam 1215 on the cam shaft 4 through a lever 1220 and a cam 1225 on the cam block 8. The cam 1225 is actuated by a cam 1230 on the cam shaft 4 through a lever 1235 and a cam 1240 on the cam block 8. The cam 1240 is actuated by a cam 1245 on the cam shaft 4 through a lever 1250 and a cam 1255 on the cam block 8. The cam 1255 is actuated by a cam 1260 on the cam shaft 4 through a lever 1265 and a cam 1270 on the cam block 8. The cam 1270 is actuated by a cam 1275 on the cam shaft 4 through a lever 1280 and a cam 1285 on the cam block 8. The cam 1285 is actuated by a cam 1290 on the cam shaft 4 through a lever 1295 and a cam 1300 on the cam block 8. The cam 1300 is actuated by a cam 1305 on the cam shaft 4 through a lever 1310 and a cam 1315 on the cam block 8. The cam 1315 is actuated by a cam 1320 on the cam shaft 4 through a lever 1325 and a cam 1330 on the cam block 8. The cam 1330 is actuated by a cam 1335 on the cam shaft 4 through a lever 1340 and a cam 1345 on the cam block 8. The cam 1345 is actuated by a cam 1350 on the cam shaft 4 through a lever 1355 and a cam 1360 on the cam block 8. The cam 1360 is actuated by a cam 1365 on the cam shaft 4 through a lever 1370 and a cam 1375 on the cam block 8. The cam 1375 is actuated by a cam 1380 on the cam shaft 4 through a lever 1385 and a cam 1390 on the cam block 8. The cam 1390 is actuated by a cam 1395 on the cam shaft 4 through a lever 1400 and a cam 1405 on the cam block 8. The cam 1405 is actuated by a cam 1410 on the cam shaft 4 through a lever 1415 and a cam 1420 on the cam block 8. The cam 1420 is actuated by a cam 1425 on the cam shaft 4 through a lever 1430 and a cam 1435 on the cam block 8. The cam 1435 is actuated by a cam 1440 on the cam shaft 4 through a lever 1445 and a cam 1450 on the cam block 8. The cam 1450 is actuated by a cam 1455 on the cam shaft 4 through a lever 1460 and a cam 1465 on the cam block 8. The cam 1465 is actuated by a cam 1470 on the cam shaft 4 through a lever 1475 and a cam 1480 on the cam block 8. The cam 1480 is actuated by a cam 1485 on the cam shaft 4 through a lever 1490 and a cam 1495 on the cam block 8. The cam 1495 is actuated by a cam 1500 on the cam shaft 4 through a lever 1505 and a cam 1510 on the cam block 8. The cam 1510 is actuated by a cam 1515 on the cam shaft 4 through a lever 1520 and a cam 1525 on the cam block 8. The cam 1525 is actuated by a cam 1530 on the cam shaft 4 through a lever 1535 and a cam 1540 on the cam block 8. The cam 1540 is actuated by a cam 1545 on the cam shaft 4 through a lever 1550 and a cam 1555 on the cam block 8. The cam 1555 is actuated by a cam 1560 on the cam shaft 4 through a lever 1565 and a cam 1570 on the cam block 8. The cam 1570 is actuated by a cam 1575 on the cam shaft 4 through a lever 1580 and a cam 1585 on the cam block 8. The cam 1585 is actuated by a cam 1590 on the cam shaft 4 through a lever 1595 and a cam 1600 on the cam block 8. The cam 1600 is actuated by a cam 1605 on the cam shaft 4 through a lever 1610 and a cam 1615 on the cam block 8. The cam 1615 is actuated by a cam 1620 on the cam shaft 4 through a lever 1625 and a cam 1630 on the cam block 8. The cam 1630 is actuated by a cam 1635 on the cam shaft 4 through a lever 1640 and a cam 1645 on the cam block 8. The cam 1645 is actuated by a cam 1650 on the cam shaft 4 through a lever 1655 and a cam 1660 on the cam block 8. The cam 1660 is actuated by a cam 1665 on the cam shaft 4 through a lever 1670 and a cam 1675 on the cam block 8. The cam 1675 is actuated by a cam 1680 on the cam shaft 4 through a lever 1685 and a cam 1690 on the cam block 8. The cam 1690 is actuated by a cam 1695 on the cam shaft 4 through a lever 1700 and a cam 1705 on the cam block 8. The cam 1705 is actuated by a cam 1710 on the cam shaft 4 through a lever 1715 and a cam 1720 on the cam block 8. The cam 1720 is actuated by a cam 1725 on the cam shaft 4 through a lever 1730 and a cam 1735 on the cam block 8. The cam 1735 is actuated by a cam 1740 on the cam shaft 4 through a lever 1745 and a cam 1750 on the cam block 8. The cam 1750 is actuated by a cam 1755 on the cam shaft 4 through a lever 1760 and a cam 1765 on the cam block 8. The cam 1765 is actuated by a cam 1770 on the cam shaft 4 through a lever 1775 and a cam 1780 on the cam block 8. The cam 1780 is actuated by a cam 1785 on the cam shaft 4 through a lever 1790 and a cam 1795 on the cam block 8. The cam 1795 is actuated by a cam 1800 on the cam shaft 4 through a lever 1805 and a cam 1810 on the cam block 8. The cam 1810 is actuated by a cam 1815 on the cam shaft 4 through a lever 1820 and a cam 1825 on the cam block 8. The cam 1825 is actuated by a cam 1830 on the cam shaft 4 through a lever 1835 and a cam 1840 on the cam block 8. The cam 1840 is actuated by a cam 1845 on the cam shaft 4 through a lever 1850 and a cam 1855 on the cam block 8. The cam 1855 is actuated by a cam 1860 on the cam shaft 4 through a lever 1865 and a cam 1870 on the cam block 8. The cam 1870 is actuated by a cam 1875 on the cam shaft 4 through a lever 1880 and a cam 1885 on the cam block 8. The cam 1885 is actuated by a cam 1890 on the cam shaft 4 through a lever 1895 and a cam 1900 on the cam block 8. The cam 1900 is actuated by a cam 1905 on the cam shaft 4 through a lever 1910 and a cam 1915 on the cam block 8. The cam 1915 is actuated by a cam 1920 on the cam shaft 4 through a lever 1925 and a cam 1930 on the cam block 8. The cam 1930 is actuated by a cam 1935 on the cam shaft 4 through a lever 1940 and a cam 1945 on the cam block 8. The cam 1945 is actuated by a cam 1950 on the cam shaft 4 through a lever 1955 and a cam 1960 on the cam block 8. The cam 1960 is actuated by a cam 1965 on the cam shaft 4 through a lever 1970 and a cam 1975 on the cam block 8. The cam 1975 is actuated by a cam 1980 on the cam shaft 4 through a lever 1985 and a cam 1990 on the cam block 8. The cam 1990 is actuated by a cam 1995 on the cam shaft 4 through a lever 2000 and a cam 2005 on the cam block 8. The cam 2005 is actuated by a cam 2010 on the cam shaft 4 through a lever 2015 and a cam 2020 on the cam block 8. The cam 2020 is actuated by a cam 2025 on the cam shaft 4 through a lever 2030 and a cam 2035 on the cam block 8. The cam 2035 is actuated by a cam 2040 on the cam shaft 4 through a lever 2045 and a cam 2050 on the cam block 8. The cam 2050 is actuated by a cam 2055 on the cam shaft 4 through a lever 2060 and a cam 2065 on the cam block 8. The cam 2065 is actuated by a cam 2070 on the cam shaft 4 through a lever 2075 and a cam 2080 on the cam block 8. The cam 2080 is actuated by a cam 2085 on the cam shaft 4 through a lever 2090 and a cam 2095 on the cam block 8. The cam 2095 is actuated by a cam 2100 on the cam shaft 4 through a lever 2105 and a cam 2110 on the cam block 8. The cam 2110 is actuated by a cam 2115 on the cam shaft 4 through a lever 2120 and a cam 2125 on the cam block 8. The cam 2125 is actuated by a cam 2130 on the cam shaft 4 through a lever 2135 and a cam 2140 on the cam block 8. The cam 2140 is actuated by a cam 2145 on the cam shaft 4 through a lever 2150 and a cam 2155 on the cam block 8. The cam 2155 is actuated by a cam 2160 on the cam shaft 4 through a lever 2165 and a cam 2170 on the cam block 8. The cam 2170 is actuated by a cam 2175 on the cam shaft 4 through a lever 2180 and a cam 2185 on the cam block 8. The cam 2185 is actuated by a cam 2190 on the cam shaft 4 through a lever 2195 and a cam 2200 on the cam block 8. The cam 2200 is actuated by a cam 2205 on the cam shaft 4 through a lever 2210 and a cam 2215 on the cam block 8. The cam 2215 is actuated by a cam 2220 on the cam shaft 4 through a lever 2225 and a cam 2230 on the cam block 8. The cam 2230 is actuated by a cam 2235 on the cam shaft 4 through a lever 2240 and a cam 2245 on the cam block 8. The cam 2245 is actuated by a cam 2250 on the cam shaft 4 through a lever 2255 and a cam 2260 on the cam block 8. The cam 2260 is actuated by a cam 2265 on the cam shaft 4 through a lever 2270 and a cam 2275 on the cam block 8. The cam 2275 is actuated by a cam 2280 on the cam shaft 4 through a lever 2285 and a cam 2290 on the cam block 8. The cam 2290 is actuated by a cam 2295 on the cam shaft 4 through a lever 2300 and a cam 2305 on the cam block 8. The cam 2305 is actuated by a cam 2310 on the cam shaft 4 through a lever 2315 and a cam 2320 on the cam block 8. The cam 2320 is actuated by a cam 2325 on the cam shaft 4 through a lever 2330 and a cam 2335 on the cam block 8. The cam 2335 is actuated by a cam 2340 on the cam shaft 4 through a lever 2345 and a cam 2350 on the cam block 8. The cam 2350 is actuated by a cam 2355 on the cam shaft 4 through a lever 2360 and a cam 2365 on the cam block 8. The cam 2365 is actuated by a cam 2370 on the cam shaft 4 through a lever 2375 and a cam 2380 on the cam block 8. The cam 2380 is actuated by a cam 2385 on the cam shaft 4 through a lever 2390 and a cam 2395 on the cam block 8. The cam 2395 is actuated by a cam 2400 on the cam shaft 4 through a lever 2405 and a cam 2410 on the cam block 8. The cam 2410 is actuated by a cam 2415 on the cam shaft 4 through a lever 2420 and a cam 2425 on the cam block 8. The cam 2425 is actuated by a cam 2430 on the cam shaft 4 through a lever 2435 and a cam 2440 on the cam block 8. The cam 2440 is actuated by a cam 2445 on the cam shaft 4 through a lever 2450 and a cam 2455 on the cam block 8. The cam 2455 is actuated by a cam 2460 on the cam shaft 4 through a lever 2465 and a cam 2470 on the cam block 8. The cam 2470 is actuated by a cam 2475 on the cam shaft 4 through a lever 2480 and a cam 2485 on the cam block 8. The cam 2485 is actuated by a cam 2490 on the cam shaft 4 through a lever 2495 and a cam 2500 on the cam block 8. The cam 2500 is actuated by a cam 2505 on the cam shaft 4 through a lever 2510 and a cam 2515 on the cam block 8. The cam 2515 is actuated by a cam 2520 on the cam shaft 4 through a lever 2525 and a cam 2530 on the cam block 8. The cam 2530 is actuated by a cam 2535 on the cam shaft 4 through a lever 2540 and a cam 2545 on the cam block 8. The cam 2545 is actuated by a cam 2550 on the cam shaft 4 through a lever 2555 and a cam 2560 on the cam block 8. The cam 2560 is actuated by a cam 2565 on the cam shaft 4 through a lever 2570 and a cam 2575 on the cam block 8. The cam 2575 is actuated by a cam 2580 on the cam shaft 4 through a lever 2585 and a cam 2590 on the cam block 8. The cam 2590 is actuated by a cam 2595 on the cam shaft 4 through a lever 2600 and a cam 2605 on the cam block 8. The cam 2605 is actuated by a cam 2610 on the cam shaft 4 through a lever 2615 and a cam 2620 on the cam block 8. The cam 2620 is actuated by a cam 2625 on the cam shaft 4 through a lever 2630 and a cam 2635 on the cam block 8. The cam 2635 is actuated by a cam 2640 on the cam shaft 4 through a lever 2645 and a cam 2650 on the cam block 8. The cam 2650 is actuated by a cam 2655 on the cam shaft 4 through a lever 2660 and a cam 2665 on the cam block 8. The cam 2665 is actuated by a cam 2670 on the cam shaft 4 through a lever 2675 and a cam 2680 on the cam block 8. The cam 2680 is actuated by a cam 2685 on the cam shaft 4 through a lever 2690 and a cam 2695 on the cam block 8. The cam 2695 is actuated by a cam 2700 on the cam shaft 4 through a lever 2705 and a cam 2710 on the cam block 8. The cam 2710 is actuated by a cam 2715 on the cam shaft 4 through a lever 2720 and a cam 2725 on the cam block 8. The cam 2725 is actuated by a cam 2730 on the cam shaft 4 through a lever 2735 and a cam 2740 on the cam block 8. The cam 2740 is actuated by a cam 2745 on the cam shaft 4 through a lever 2750 and a cam 2755 on the cam block 8. The cam 2755 is actuated by a cam 2760 on the cam shaft 4 through a lever 2765 and a cam 2770 on the cam block 8. The cam 2770 is actuated by a cam 2775 on the cam shaft 4 through a lever 2780 and a cam 2785 on the cam block 8. The cam 2785 is actuated by a cam 2790 on the cam shaft 4 through a lever 2795 and a cam 2800 on the cam block 8. The cam 2800 is actuated by a cam 2805 on the cam shaft 4 through a lever 2810 and a cam 2815 on the cam block 8. The cam 2815 is actuated by a cam 2820 on the cam shaft 4 through a lever 2825 and a cam 2830 on the cam block 8. The cam 2830 is actuated by a cam 2835 on the cam shaft 4 through a lever 2840 and a cam 2845 on the cam block 8. The cam 2845 is actuated by a cam 2850 on the cam shaft 4 through a lever 2855 and a cam 2860 on the cam block 8. The cam 2860 is actuated by a cam 2865 on the cam shaft 4 through a lever 2870 and a cam 2875 on the cam block 8. The cam 2875 is actuated by a cam 2880 on the cam shaft 4 through a lever 2885 and a cam 2890 on the cam block 8. The cam 2890 is actuated by a cam 2895 on the cam shaft 4 through a lever 2900 and a cam 2905 on the cam block 8. The cam 2905 is actuated by a cam 2910 on the cam shaft 4 through a lever 2915 and a cam 2920 on the cam block 8. The cam 2920 is actuated by a cam 2925 on the cam shaft 4 through a lever 2930 and a cam 2935 on the cam block 8. The cam 2935 is actuated by a cam 2940 on the cam shaft 4 through a lever 2945 and a cam 2950 on the cam block 8. The cam 2950 is actuated by a cam 2955 on the cam shaft 4 through a lever 2960 and a cam 2965 on the cam block 8. The cam 2965 is actuated by a cam 2970 on the cam shaft 4 through a lever 2975 and a cam 2980 on the cam block 8. The cam 2980 is actuated by a cam 2985 on the cam shaft 4 through a lever 2990 and a cam 2995 on the cam block 8. The cam 2995 is actuated by a cam 3000 on the cam shaft 4 through a lever 3005 and a cam 3010 on the cam block 8. The cam 3010 is actuated by a cam 3015 on the cam shaft 4 through a lever 3020 and a cam 3025 on the cam block 8. The cam 3025 is actuated by a cam 3030 on the cam shaft 4 through a lever 3035 and a cam 3040 on the cam block 8. The cam 3040 is actuated by a cam 3045 on the cam shaft 4 through a lever 3050 and a cam 3055 on the cam block 8. The cam 3055 is actuated by a cam 3060 on the cam shaft 4 through a lever 3065 and a cam 3070 on the cam block 8. The cam 3070 is actuated by a cam 3075 on the cam shaft 4 through a lever 3080 and a cam 3085 on the cam block 8. The cam 3085 is actuated by a cam 3090 on the cam shaft 4 through a lever 3095 and a cam 3100 on the cam block 8. The cam 3100 is actuated by a cam 3105 on the cam shaft 4 through a lever 3110 and a cam 3115 on the cam block 8. The cam 3115 is actuated by a cam 3120 on the cam shaft 4 through a lever 3125 and a cam 3130 on the cam block 8. The cam 3130 is actuated by a cam 3135 on the cam shaft 4 through a lever 3140 and a cam 3145 on the cam block 8. The cam 3145 is actuated by a cam 3150 on the cam shaft 4 through a lever 3155 and a cam 3160 on the cam block 8. The cam 3160 is actuated by a cam 3165 on the cam shaft 4 through a lever 3170 and a cam 3175 on the cam block 8. The cam 3175 is actuated by a cam 3180 on the cam shaft 4 through a lever 3185 and a cam 3190 on the cam block 8. The cam 3190 is actuated by a cam 3195 on the cam shaft 4 through a lever 3200 and a cam 3205 on the cam block 8. The cam 3205 is actuated by a cam 3210 on the cam shaft 4 through a lever 3215 and a cam 3220 on the cam block 8. The cam 3220 is actuated by a cam 3225 on the cam shaft 4 through a lever 3230 and a cam 3235 on the cam block 8. The cam 3235 is actuated by a cam 3240 on the cam shaft 4 through a lever 3245 and a cam 3250 on the cam block 8. The cam 3250 is actuated by a cam 3255 on the cam shaft 4 through a lever 3260 and a cam 3265 on the cam block 8. The cam 3265 is actuated by a cam 3270 on the cam shaft 4 through a lever 3275 and a cam 3280 on the cam block 8. The cam 3280 is actuated by a cam 3285 on the cam shaft 4 through a lever

to about 70 degrees. The other stage (b) occurs between the conclusion of the tack driving operation and the end of the cycle and amounts to about 100 degrees.

5 The purpose of the present invention as embodied in a machine of the kind described is to prolong the time during which the cam shaft is given the 40-degree movement above mentioned for updrawing the 10 upper so that this operation will be more slowly and effectively performed, and to make up the time lost in this operation during the stages (a) and (b) above explained during which no effective work is 15 being done by the machine which would be disturbed by the necessary acceleration of the cam shaft to make up the lost time.

As shown herein the mechanism for this purpose comprises a driving member or pulley 44 which may be loosely mounted on 20 the end portion of the cam shaft 4 or may be on a separate shaft coaxial with the shaft 4 and supported for rotation in any suitable manner, the only essential being 25 that the driving pulley 44 be arranged for rotation at uniform angular velocity when the machine is in normal operation and have positive driving connection with a member or arm 46 which, therefore, is 30 driven at constant angular velocity. On the outer end of the arm 46 is fixed a pin 48 on which is rotatably mounted a block 50. The block 50 slides in a slot 52 formed in one corner of a triangular lever 54 which, 35 at another corner, is pivoted at 56 to an arm 58 fast on the cam shaft 4. The third corner of the lever 54 carries a cam roll 60 which is held by a spring 62 against the edge of a stationary cam 64 which is 40 fixed at 61, 63 to a suitable part of the machine frame, the spring being sufficiently strong to maintain the roll 60 at all times against the cam 64. It will be evident that if the member 46 is rotated at a uniform 45 angular velocity the cam 64 will, at all parts concentric with the cam shaft, cause the member 58 to be rotated at the same angular velocity but that an inclined portion of the cam will cause a change of relative speeds 50 of the parts 46 and 58, an increasing radius of the cam causing a decrease in the speed of the arm 58 and consequently of the cam shaft and vice versa.

The acting edge face of the cam 64 is 55 concentric with the shaft for the first 100 degrees reckoned from the normal position of the cam roll 60 when the machine is started, the grippers during this period being lowered and closed upon the upper. 60 The cam is then shaped to move the cam roll 60 outwardly with respect to the shaft so that an angular movement of 80 degrees of the driven member 46 is required to advance the cam shaft 4 through the next 40 65 degrees. This results in slowing down below

the hitherto normal speed the speed of the cam operated parts during this 40-degree portion. As stated the retardation is such as to give the 40-degree portion of the cycle about twice the normal time for its performance. Since this slowing down is effected by the shape of this portion of the cam it will be appreciated that the deceleration may be either uniformly distributed 70 over the 40-degree portion or may be greater 75 at one part of it than at another, as desired. For instance, it may be preferred to cause the whole of the slowing down or deceleration to occur in the early part 80 of the 40-degree portion, that is, before the overdraw occurs.

During the next 70 degrees of movement of the member 46 the cam is shaped to permit the roll 60 to approach the shaft with a consequent increase of the angular movement of the shaft 4 relatively to that of the member 46. As shown the angular movement of the shaft will be, during this portion, about 50 degrees, this being the first stage (a), that is, the stage between the 85 conclusion of the deceleration or the end of the said 40-degree portion and the commencement of the overwiping on the shoe bottom by the wiper 34. From the point now reached the cam is concentric for about 90 50 degrees during which the overwiping and tacking operations are effected. These operations, therefore, are conducted under exactly the same speed conditions as in the past. From this point the cam 64 allows 95 the roll 60 further to approach the shaft during the remainder of the rotation constituting 100 degrees of stage (b) above referred to. During this period the speed 100 of the member 58 is accelerated so that the remainder of the lost time is made up. Thus the making up of the time lost during the updraw is localized to occur during two separated portions of the remainder of the cycle, about one-half being made up during 105 70 degrees of stage (a) and the remainder during the 100 degrees or thereabouts of stage (b). The result of thus dividing and localizing the making up of the time lost during the updraw is that the cam shaft 110 115 is accelerated during those portions of the cycle when the operating instrumentalities are not actively engaged upon the work and hence have no effort upon the operation 120 of the machine.

In order that the cam shaft 4 of the machine may be run at uniform speed as heretofore, if desired, it is only necessary to provide a hole 66 in the member 46 so located that when the cam roll 60 is at 125 the outer limit of its movement as shown in dotted lines in Fig. 2, the hole will be in registration with the center of the pin 56 in which a hole corresponding to the hole 66 is made so that by putting a pin through 130

the hole 66 into the hole 68 the parts will be locked against movement and the cam 64 become inoperative.

The result effected by application of the present invention to the hand method machine is, therefore, that the operations of wiping the upper over the shoe bottom and of inserting a tack are performed under exactly the same speed conditions as in the past, and that throughout the lasting of the shoe around the sides, shank, heel and toe portions in each cycle the cam shaft will automatically slow down for a short time to give longer time than was hitherto available for the stretching of the upper without any attention on the part of the operator and without diminution of the output of lasted shoes.

Having thus described my invention, what I claim as new and desire to secure by Letters Patent of the United States is:

1. In a machine having instrumentalities for effecting successive operations upon the work, the combination of operating means common to the instrumentalities for operating them in timed relation, a driving member arranged for rotation at a uniform angular velocity, and means between the driving member and said operating means acting to retard movement of said operating means relatively to the driving member while one of said instrumentalities is operating and for accelerating movement of said operating means above that of the driving member at another time in the cycle of the machine.

2. In a machine having instrumentalities for effecting successive operations upon the work, the combination of a shaft for operating the instrumentalities in succession, a driving member arranged for rotation at uniform angular velocity, and means between the driving member and the shaft for automatically varying the angular velocity of the shaft relatively to that of the driving member to prolong the time given to the operation of one of said instrumentalities and to make up the time lost in other portions of the cycle.

3. In a machine having instrumentalities for effecting successive operations upon the work, the combination of operating means common to said instrumentalities and capable of operating the instrumentalities in a given normal timed relation if moved at a uniform speed, a driving member arranged to be rotated at a uniform angular velocity, and means between the driving member and said common operating means acting in each cycle to retard at one time and to accelerate at another time the movement of the common operating means relatively to the uniform movement of the driving member and consequently to vary the normal timed relation of the operation of said instrumen-

talities without affecting the normal time occupied by the cycle.

4. In a machine having instrumentalities for effecting successive operations upon the work in each cycle, a cam shaft having a series of cams, connections from said cams to said instrumentalities for operating the instrumentalities in a given timed relation when the shaft is turned at uniform angular velocity, a driving member arranged to be driven at uniform angular velocity, and means between the driving member and the shaft acting to modify the relative timing of said instrumentalities while maintaining the number of revolutions of the driving member and the cam shaft the same.

5. In a machine having instrumentalities for effecting successive operations upon the work in each cycle, a shaft, a driving member arranged to be rotated at a uniform angular velocity, a master cam, and connections between the driving member and the shaft under control of the master cam for varying the angular velocity of the shaft relatively to the driving member to give greater operating time to one of said instrumentalities and to make up time in other portions of the cycle.

6. In a machine for operating on shoes, the combination with means for performing different operations on a shoe successively in the course of the cycle of operations of the machine, of power driven operating mechanism, and means automatically operative in each cycle to drive said operating mechanism at a slower rate during one portion of the cycle and to drive said mechanism at a faster rate in another portion of the same cycle.

7. In a machine for operating on shoes, the combination with means for performing different operations on a shoe successively in the course of the cycle of operations of the machine, of power driven operating mechanism, and means automatically operative in each cycle to decelerate movement of the operating mechanism during one portion of the cycle and to produce a corresponding acceleration in the remainder of the same cycle.

8. In a machine for operating on shoes, the combination with means for performing different operations on a shoe successively in the course of the cycle of operations of the machine, of power driven operating mechanism, and means automatically operative in each cycle to decelerate movement of the operating mechanism during one portion of the cycle and to make up the time lost in localized portions of the remainder of the same cycle.

9. In a machine for operating on shoes, the combination with means for performing different operations on a shoe successively in the course of the cycle of operations of

the machine, of power driven operating mechanism, and means automatically operative in each cycle to decelerate movement of the operating mechanism during one portion of the cycle and to effect acceleration in two stages of the remainder of the cycle.

10. In a machine for operating on shoes, the combination with mechanism for performing different operations on a shoe successively in the course of operations of the machine, of power driven operating means, and means automatically operative in each cycle to cause movement of the operating mechanism during one operation of the cycle, to take more than normal time to make up the time lost by increasing the speed of the operating mechanism above normal in portions of the remainder of the cycle located between the remaining operations, and to perform the remaining operations at normal speed.

11. In a machine having instrumentalities for effecting successive operations upon a shoe, a driving member to be rotated at a uniform angular velocity, a shaft for operating the instrumentalities in normal timed relation, and means between the driving member and the shaft to give greater than normal operating time to one of said instrumentalities during a portion of the cycle and to make up the time in other portions of the cycle.

12. In a machine having a plurality of instrumentalities for effecting successive operations upon a shoe, a driving member to be rotated at a uniform angular velocity, a shaft and connecting mechanism for operating the instrumentalities in normal timed relation, and means between the driving member and the shaft for decreasing the angular velocity of the shaft relatively to that of the driving member to prolong the time given to the operation of one of said instrumentalities and then to increase the angular velocity of the shaft to maintain the total time occupied by the operation of all of the instrumentalities unchanged.

13. In a machine having instrumentalities for effecting successive operations, a driving member to be rotated at a uniform angular velocity, a shaft and connecting mechanism for operating the instrumentalities in a given timed relation, a master cam, and connections between the driving member and shaft under control of the master cam for varying the angular velocity of the shaft to prolong the time during which one of said instrumentalities is operating and to make up the lost time in other portions of the cycle.

14. In a machine having instrumentalities for effecting successively upper stretching, overwiping and tacking operations upon a shoe upper, the combination of operating

means common to the instrumentalities for operating them in timed relation, a driving member arranged for rotation at a uniform angular velocity, and means between the driving member and said operating means acting to retard movement of said operating means relatively to the driving member while the stretching instrumentality is operating and for accelerating movement of said operating means above that of the driving member at another time in the cycle of the machine.

15. In a machine having instrumentalities for effecting successively upper stretching, overwiping and tacking operations upon a shoe upper, the combination of a shaft for operating the instrumentalities in succession, a driving member arranged for rotation at uniform angular velocity, and cam controlled means between the driving member and the shaft for automatically reducing the angular velocity of the shaft below to that of the driving member to prolong the time given to the operation of the upper stretching instrumentality and increase the angular velocity of the shaft above that of the driving member at other time in the cycle than that occupied by the overwiping and tacking operations.

16. In a machine for operating on shoes, means for stretching an upper, means for overwiping and tacking the upper, a cam shaft having a series of cams, connections from said means to the cam shaft such that uniform angular rotation of the shaft would be imparted to all of said means and cause them to act in predetermined timed relation, during a cycle driving means rotated at uniform angular velocity to apply power to said shaft, and cam controlled connections between said driving means and the cam shaft for diminishing and increasing the angular velocity of the cam shaft relatively to the uniform velocity of the driving means in such manner as to set up a new time relation between the stretching operation and the wiping and tacking operations while maintaining the time occupied by the cycle unchanged.

17. In a machine for operating on shoes, means for stretching an upper, means for overwiping the upper, means for tacking the upper, a cam shaft having a series of cams, connections from said means to the cam shaft such that uniform angular rotation of the shaft would impart motion to all of said means and cause them to act in a predetermined timed relation, means rotated at uniform angular velocity to apply power to said shaft, a master cam, and connections from said power applying means to the cam shaft controlled by the master cam for diminishing and increasing the angular velocity of the cam shaft to establish a time relation different from said pre-

- terminated time relation in such manner that the stretching operation takes place slowly and the time lost in this operation is made up at other times in the cycle.
- 5 18. In a machine having a plurality of instrumentalities for performing in succession a plurality of operations upon a shoe in each cycle of a succession of uninterruptedly repeated cycles, the combination of a member 10 arranged to be rotated at uniform angular velocity, means for operating said instrumentalities from said member, and means for automatically varying in each cycle the velocity given to said operating means while some instrumentalities are operated relatively to the velocity given to the operating means when other instrumentalities are being operated.
- 15 19. In a machine for lasting successive portions of an upper progressively along the periphery of a shoe, means for updrawing the upper, means for overwiping and tacking the upper, a cam shaft for operating said means, means driven at constant speed for applying power to said shaft, and means between the power applying means and the shaft for effecting a deceleration of the movement of the shaft below said constant speed during the updraw movement and an acceleration of the shaft above said constant speed prior to the action of the overwiping means.
- 20 20. In a machine for lasting successive portions of an upper progressively along the periphery of a shoe, means for updrawing the upper, means for overwiping and tacking the upper, a shaft for operating said means, means driven at constant speed for applying power to said shaft, and means between the power applying means and the shaft for effecting during a portion of each cycle a deceleration of the movement of the shaft below said constant speed during the updraw movement, for effecting acceleration of the movement of the shaft above said constant speed during another portion of the cycle to maintain the time for the complete cycle unchanged and for effecting the overwiping and tacking operation at said constant speed.
- 25 21. In a machine for lasting successive portions of an upper progressively along the periphery of a shoe, means for updrawing the upper, means for overwiping and tacking the upper, a cam shaft for operating said means, rotary means driven at uniform angular velocity for applying power to said shaft, a stationary cam, and rotating means between the power applying means and the shaft under control of the cam for effecting a deceleration of the updraw movement.
- 30 22. In a machine for lasting successive portions of an upper over a last progressively along the periphery of a shoe, means for updrawing the upper, a cam shaft for shafting and tacking the upper, a cam shaft for operating said means, means for applying power to said shaft, and means between the power applying means and the shaft for effecting a deceleration of the shaft during the updraw movement and an acceleration of the shaft between the updraw and the wiping operations and between the tacking operation and the end of the cycle.
- 35 23. In a machine for lasting successive portions of an upper over a last progressively along the periphery of a shoe, means for updrawing the upper, means for overwiping and tacking the upper, a cam shaft for operating said means in normal timed relation, means for applying power to said shaft, and means between the power applying means and the shaft for increasing above normal the time devoted to the updrawing operation, maintaining the time occupied by wiping and tacking operations unchanged, and reducing below normal the time occupied by other portions of the cycle.
- 40 24. In a machine for lasting successive portions of an upper over a last progressively along the periphery of a shoe, means for updrawing the upper, means for overwiping and tacking the upper, a cam shaft for operating said means, rotating means having a uniform angular velocity for applying power to said shaft, and means between the said rotating means and the shaft for effecting a deceleration of the shaft relatively to the rotating means to slow down the movement of the updrawing means and acceleration of the shaft above the angular velocity of the rotating means after the updrawing operation and prior to the wiping operation.
- 45 25. In a machine for lasting successive portions of an upper over a last progressively along the periphery of a shoe, means for updrawing the upper, means for overwiping and tacking the upper, a cam shaft for operating said means, rotating means for applying power to said shaft to rotate it, and means between the power applying means and the shaft for reducing the angular velocity of the shaft below that of the power applying means to increase the time devoted to the updrawing movement and increasing the angular velocity of the shaft above that of the power applying means during a portion of the remainder of the cycle.
- 50 26. In a machine for lasting successive portions of an upper over a last progressively along the periphery of a shoe, means for updrawing the upper, means for overwiping and tacking the upper, a cam shaft for operating said means, rotary means for driving said shaft, and cam controlled means between the rotary driving means and the shaft acting to diminish the angular velocity of the shaft below that of the rotary driv-

ing means to cause movement of the updrawing means to take place slowly and to increase the angular velocity of the shaft above that of the rotary driving means 5 after the completion of the updrawing operation and after the wiping and tacking operations.

27. In a machine for lasting successive portions of an upper over a last progressively along the periphery of a shoe, means for updrawing the upper, means for overwiping and tacking the upper, a cam shaft for operating said means, rotating means for applying power to said shaft, and means 10 between the power applying means and the shaft for reducing the angular velocity of the shaft relatively to that of the power applying means to increase the time devoted to the updrawing operation, maintaining the 15 angular velocity of the shaft the same as that of the power applying means during the wiping and tacking operations, and increasing the angular velocity of the shaft relatively to that of the power applying 20 means at other times in the cycle to make up the time lost during the updrawing operation.

28. In a machine of the class described, the combination of a rotary driving member, 25 a rotary driven member, means for connecting the said members to cause one to be driven from the other, a roll on said connecting means, and a stationary cam contoured to impart movement to the roll radially of said rotary members and cause 30 the angular velocity of one rotary member to be varied relatively to that of the other rotary member.

29. In a machine of the class described, 35 the combination of two rotary members, connections to cause one of said members to be rotated by the other member in the same direction, a roll on the connecting means, and a cam engaged by said roll 40 constructed and arranged to cause movement of the roll substantially radially of said members and to effect movement of said connecting means to cause relative 45 angular movements of said members during 50 their rotation.

30. In a machine of the class described, 55 the combination of a rotary driving member, a rotary driven member arranged in coaxial relation, a stationary cam, and a three-arm lever having one arm pivotally connected 60 to the driving member at a distance from its axis, one arm pivoted to the driven member at a less distance from its axis and the third arm carrying a roll engaging said cam, 65 said elements being constructed and arranged to cause a constant angular velocity

of the driving member to impart varying angular velocity to the driven member.

31. In a machine of the class described, 70 the combination of a rotary driving member, a rotary driven member arranged in coaxial relation, a stationary cam, a triangular lever having at one corner a pin-and-slot pivotal connection to the driving member at a distance from its axis, having 75 pivotal connection at another corner to the driven member at a less distance from its axis, and having at the third corner a roll engaging the cam, the cam being contoured to cause uniform angular movement of the 80 rotary driving member to impart to the driven member decreased and increased angular velocities relatively to that of the driving member.

32. A machine of the class described 85 having, in combination, a driving member, a driven shaft having an arm, a triangular lever having one corner pivotally connected to the driving member, one corner pivoted to the arm of the driven shaft and the third 90 corner carrying a roll, and a cam engaged by said roll and contoured to cause a constant angular velocity of the driving member to impart varying angular velocities to the 95 driven shaft.

33. In a machine of the class described, the combination of a rotary driving member and a rotary driven member arranged in coaxial relation, a stationary cam, and a three-arm lever having one arm pivoted to 95 the driving member, one arm pivoted to the driven member and the third arm carrying a roll engaging said cam, all of said elements being constructed and arranged to cause a constant angular velocity 100 of the driving member to impart varying angular velocity to the driven member.

34. In a machine of the class described, the combination of a shaft having an arm fixed thereto, a driving member including 105 an arm rotatable coaxially of the shaft, means for connecting one arm to the other arm to cause uniform angular movement of the driving arm to impart the same angular movement to the arm on the shaft 110 when the position of said connecting means relatively to the arms is maintained unchanged, a cam roll on said connecting means, and a fixed cam engaged by said roll and contoured to vary the position of said 115 connecting means relatively to the arms and hence to cause the angular velocities of the arms to be relatively varied.

In testimony whereof I have signed my name to this specification.

ARTHUR BATES.
